UNITED STATES PATENT OFFICE.

CHARLES VIVIAN WEATHERS, OF SAN JOSE, CALIFORNIA.

SHOCK-ABSORBING SPRING FOR GUN-STOCKS.

~~BEST AVAILABLE COPY~~

1,086,490.

Specification of Letters Patent. Patented Feb. 10, 1914.

Application filed September 29, 1913. Serial No. 792,406.

To all whom it may concern:

Be it known that I, CHARLES VIVIAN WEATHERS, a citizen of the United States, residing at San Jose, in the county of 5 Santa Clara and State of California, have invented a new and useful Improvement in Shock-Absorbing Springs for Gun-Stocks, of which the following is a specification.

My invention is designed to be attached 10 upon the heel end of a gun stock for the purpose of taking up the shock resulting from the firing of a heavily loaded gun, thus preventing bruising of the shoulder of the user, and many other accidents which 15 often occur when a gun is over loaded.

The primary object of my invention is to provide a generally improved shock absorbing spring of the class described, which will be exceedingly simple in construction, 20 cheap of manufacture, efficient in use, and much better adapted to its intended purposes than any other device of the same class, with which I am acquainted.

Another object of my invention is to provide a shock absorbing spring for a gun stock that will be easy of adjustment and efficient in operation and one that can be fastened to the stock of a gun without mutilating the same.

With the above mentioned ends in view, 30 my invention consists in the novel construction, arrangement, and combination of parts hereinafter described, and illustrated in the accompanying drawings, and particularly 35 pointed out in the appended claims.

Referring to the drawings, forming a part of this specification, Figure 1 is a side elevation of my shock absorbing spring for gun stock attached to said gun stock. Fig. 2 40 is a vertical, longitudinal section through the shock absorbing spring attached to a gun stock, parts being broken away. Fig. 3 is a perspective view of my shock absorbing spring for gun stock.

Similar numerals of reference designate like parts throughout all the figures of the drawings.

Referring to the drawings, the numeral 1 designates a gun stock, 2 is a shock absorbing spring having an inner and an outer plate, and is attached to the gun stock 1 by

screws shown at 3 which pass through the inner plate of spring 2 and hold the inner plate snugly against the end of the gun stock 1, leaving the outer portion of said 55 spring 2 resilient. Said outer portion has a guide bar 4 passing into a slot 5 cut through the upper portion of inner plate of spring 2, and extending a distance therethrough. This guide 4 is for the purpose of guiding 60 the upper portion of the resilient part of spring plate 2 in a direct line when the spring thereof receives the shock. Near the lower end of said resilient part of spring plate 2 is a hole 6 bored through said 65 resilient plate for the purpose of inserting therethrough screw 3 which assists in fastening inner plate of spring 2 to gun stock 1. Said shock absorbing spring 2 is made of steel or any other suitable spring metal of 70 the proper thickness and width, bent and formed in shape as shown in the drawings, having an inner and an outer member. Said inner member is fastened to a gun stock as shown at 3, leaving said outer member resilient, which breaks the recoil of the gun and diminishes the force of the recoil when heavier charges are used, and dispenses with the annoyances caused by the recoiling, and gives a better aim and greater 80 force to the gun with the same charge as when the ordinary plate is used therewith.

From the foregoing description, taken in connection with the accompanying drawings, the operation and advantages of my invention will be readily understood.

Having thus described my invention, what I claim and desire to secure by Letters Patent, is—

1. An improvement in a shock absorbing 85 spring for gun stocks, the combination of an inner and an outer plate and means for fastening the same to a gun stock, said outer portion of said spring being resilient and having a guide bar adapted to pass through 90 a slot cut through the upper portion of the inner plate of said spring and extending a distance therethrough, substantially as and for the purpose set forth.

2. An improvement in a shock absorbing 100 spring for gun stocks made of steel or any other suitable spring metal of the required

width and thickness bent and formed in the shape substantially as shown in the drawings, said spring having an inner and an outer member, said inner member being fastened to a gun stock, said outer member being resilient, substantially in the manner and for the purpose set forth.

In testimony whereof I have affixed my signature, in the presence of two subscribing witnesses

CHARLES VIVIAN WEATHERS.
